UNITED STATES PATENT OFFICE

TEX O'ROURKE, OF NEW YORK, N. Y., ASSIGNOR, BY MESNE ASSIGNMENTS, TO CARD DISPLAY, INC., OF NEW YORK, N. Y., A CORPORATION OF NEW YORK

CARD DISPLAY STAND

Application filed September 8, 1930. Serial No. 480,312.

The device of the present invention, while capable of a wide range of utility, is peculiarly adapted for embodiment in a portable self-supporting stand adapted to mount assembled sign cards and price cards.

The device is particularly useful in connection with counter displays of merchandise in department stores and other high class shops.

10 An object of the invention is to provide a card display stand which will permit the convenient assembly of a series of interchangeable character-bearing tiles or cards within a frame which is designed to expedite and 15 facilitate replacement of any card and serves effectively to protect the edges of the cards against casual abrasion.

20 A more specific object is to provide a display card carrier frame in which certain of the cards, when in applied position, serve to lock other cards against inadvertent displacement so that the frames with the cards assembled therein may be conveniently transported without danger of the cards falling 25 out, more specifically without any danger of the relatively small character-bearing price card members becoming displaced or disarranged.

Another object is to provide a stand of this 30 character which is unapt to be accidentally upset in use, and yet, which may be conveniently laid on its side when the merchandise displays are covered at night, without danger of injuring the cards or of having any of the 35 cards displaced.

Another object is to provide a carrier frame which is peculiarly adapted for receiving small interchangeable character bearing tiles and which is so designed that one or more of 40 the tiles may be readily interchanged without the necessity for displacing the entire row of tiles and the tiles when in position will have all of their non-abutting edges adequately protected against abrasion.

45 The stand is of simple, rugged, durable construction well suited to meet the demands of economic manufacture and to withstand the careless handling to which it may be subjected.

50 In a preferred embodiment of the inven-

tion, a standard, rising from a suitable base, supports a card carrying structure consisting of three superimposed card receiving frames. Slidable insertion of cards into one of said frames serves to block withdrawal of the card 55 or cards from an adjacent frame. The frame structure is preferably defined by a pair of similar stamped front and back frame members connected by a skeleton filler assemblage of short intermediate frame members. The 60 skeleton filler pieces are so constructed and designed that there is little waste of stock in stamping them out, and they are so shaped that a minimum number of rivets or securing devices may be employed when assembling the skeleton pieces between the front 65 and rear frame sections. In fact, I prefer to so shape some of the skeleton filler bars that they interlock with each other to prevent relative displacement, whereby their retention 70 is effected by using a few rivets and relying on the interlocking structure to hold certain of the parts against relative displacement.

The invention may be more fully understood from the following description taken in 75 connection with the accompanying drawings wherein

Fig. 1 is a front elevational view of a display stand embodying the invention.

Fig. 1-a is a sectional plan view on the 80 line 1a-1a of Fig. 1.

Fig. 2 is an enlarged broken vertical sectional view taken approximately on the line 2-2 of Fig. 1.

85 Figs. 3, 4, and 5 are enlarged transverse sectional views taken, respectively, on the lines 3-3, 4-4, and 5-5 of Fig. 1.

Fig. 6 is a view mainly in a front elevation of the card-carrying portion of the stand, 90 the parts being broken away for clearness and the various sign cards being shown partially withdrawn from their respective frames in order to illustrate the manner of insertion of the cards.

95 Fig. 7 is a disassembled perspective view of the two outer frame sections and the filler pieces which coact with such sections to define the card holding frames.

Figs. 8, 9 and 10 are enlarged sectional 100

details through various portions of the assembled frames.

The means herein set forth are similar in some degree to the device of my copending application Serial Number 425,103 filed February 1, 1930.

As best seen in Fig. 1, the display stand consists generally of the base portion, B, from which rises the standard, S, upon the upper end of which is mounted the card-carrying frame assemblage designated generally at F.

The base, B, may conveniently comprise one or more base plates, 10. Two plates are here shown in superimposed relationship, the lower plate having cushioning feet, 11, at its corners. The standard, S, is formed by a suitable length of rod or bar stock, 12, the reduced threaded upper end, 13, of which screws into socket, 14, in a coupling piece, 15, which supports the frame assemblage, F, this coupling piece at its lower end abutting the shoulder, 16, defined by the reduced end, 13, of the rod, 12. At the lower end of the rod, 12, there is also provided a reduced threaded extension, 17, passing through aligned apertures, 18, in the base plates, 10, and retained by a nut, 19, which works in a recess, 20, in the lower base plate. The upper base plate may also have a recess, 21, in its upper face to accommodate the shoudered portion of the rod, 12, which is above the extension, 17.

The card-carrying frame assemblage, F, may be designed to provide any suitable number of card framing openings. For illustrative purposes, three of such openings are provided and designated generally by the numerals, 22, 23 and 24. The frame structures which define these three framing openings are each channelled to accommodate the edges of the display cards to be carried in the frames and are each open on one fourth side to admit of convenient application or removal of the cards.

The manner in which these channels are formed appears most clearly from Fig. 7 wherein the various elements of the frame structure, F, are shown in disassembled relationship. This frame structure includes a pair of unitary front and back sections, 25, of identical construction and comprising skeleton frames stamped from a single piece of sheet material and presenting three elongated openings, arranged in side by side or superimposed relationship. Each member, 25, includes a top bar, 26, and a bottom bar, 27, connected by side bars, 28, which in turn are bridged by two intermediate cross bars, 29 and 30, thus defining the three openings, 31, 32, and 33.

The skeleton filler structure includes a generally U shaped member, 34, the elongated central bar of which lies between the lower cross bars, 27, of the frames, 25, and the

arms, 35, of which rise between the end bars of the framing openings, 33. Short filler sections, 36 and 37, are adapted to lie between the sections of the left hand frame bars, 28, which close the ends of the openings, 32 and 31, respectively. A skeleton cross bar, 38, is adapted for disposition between the cross bars, 29, of the frames, 25, and a short skeleton frame piece, 39, is adapted to lie between the upper ends of the frame bars, 29, which close the right hand end of the top framing opening, 31.

In order to minimize the riveting operations necessary to secure the two outer frame members and the skeleton filler structure together, the adjacent ends of the pieces, 36 and 37, are rounded out as at 40, to interlock with the correspondingly rounded end, 41, of the filler piece, 38. Similarly, the lower end of the piece, 39, is rounded at 42, to fit with the correspondingly rounded end, 43, of the member, 38. Also, the lower end of the filler piece, 36, is formed with a curved recess, 44, to receive and interlock with a rounded extension, 45, at the top of the left hand arm, 35. The right hand arm, 35, terminates in a flat top having a cutaway portion, 46, to present an inwardly facing shoulder, 47, the purpose of which will be more fully thereafter set forth.

In assembling the frames, 25, and the filler pieces, rivets 46, are used at the upper corners of the frames, 25, these rivets passing through the upper ends of these filler pieces, 37 and 39. Rivets, 47, are used at the ends of the cross bars, 29, these rivets passing through the ends of the filler bar, 38. Rivets, 48, connect opposite ends of the lower cross bars, 27, with the cross bar, 34, and rivets, 49, connect the ends of the cross bars, 30, with the upper ends of the arms, 35. It will thus be seen that neither end of the member, 36, is riveted and that the lower ends of the members, 37 and 39, are not riveted, rivets being eliminated by the use of the interlocking structure whereby these unriveted ends are blocked against movement by their engagement with the rounded ends of the members, 35 and 38, respectively.

A frame structure when thus assembled, may be conveniently mounted on the standard by inserting the projecting lower edge of the cross bar, 34, into a slot, 50, in the top of the coupling piece, 15, and riveting, as at 51. Preferably all of the rivet holes are formed as an incident of stamping out the various frame pieces in order to facilitate subsequent assembly.

With the parts assembled as above described, it will be seen that the upper framing opening, 22, is open at its top for the reception of a sign card and has a channelled bottom and channelled side portions to receive the edges of the card, these channels being afforded by the difference in the width

of the frame bars, 28 and 29, and the filler pieces, 37, 39 and 38. The lower framing opening, 24, is similarly open at its top and is provided with a channelled bottom and channelled sides. The central framing opening, 23, is open at one side and closed at its other side, its closed top is channelled and a card in said frame rests at its lower end on the cutaway portion, 46, of one arm, 35, and the correspondingly cutaway portion, 46-a, of the opposite arm.

Preferably the lower framing opening, 24, is adapted to receive a plurality of small character-bearing tiles, 60, arranged in side by side abutting relationship and serving to cooperatively display the prices of the articles on the counter. These tiles are dropped in through the open top of the lowermost frame and upward movement thereof is blocked by the slidable insertion of a card, 61, into the central frame. This card rests on the supporting surfaces, 46', 46-a, as above described, and as it drops behind the shoulder, 47, it is safely guarded against accidental withdrawal. A card, 62, may be dropped into the uppermost frame through the open top thereof.

It will be evident that the frame construction is admirably adapted for use of the small character bearing cards or tiles in the lower frame, since such cards may be readily interchanged and removed as desired without disturbing the entire row of tiles as would be the case if the tiles had to be slipped out through an end opening rather than a top opening in the lower framing section.

In practice, a set of price cards, ordinarily of cardboard, as well as the cards, 61 and 62, may be duplicated, two sets being placed back to back as illustrated so that the sign may be read from either side. If desired, a filler piece shown at 63 on Fig. 2 may be employed between the sets of price card tiles, 60, to strengthen and reinforce them.

By using the three frames, it is quite convenient to display the price of the merchandise in one frame, the name of the merchandise in another frame, and either the name of the department in which the merchandise is sold or the particular holiday or sales event being celebrated, in the third frame.

It will thus be seen that there is herein described an article in which the several features of this invention are embodied, and which article in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a

limiting sense, for the invention is to be construed as broadly as it is recited in the appended claims.

Having thus described my invention, what I claim as new and desire to secure by Letters Patent of the United States is:—

1. A display device of the class described, including a pair of generally similar coinciding outer frame members and spacer means fixed between the same and cooperating with them to define a plurality of card holding frames, each having an opening in a side through which a card may be slidably applied, only one of said openings leading directly to the exterior of said device, the card receiving opening in the side of one frame being through the side of another frame and at right angles to the receiving opening for the card to be mounted in said other frame, whereby withdrawal of a card from the first frame is blocked by the card in the second frame.

2. A display device of the class described, including a pair of generally similar coinciding outer frame members and spaced means interposed between and connected to them and cooperating with the outer frame members to define a pair of adjacent channeled frames, one of said frames being in communication through an opening at one side with the other and adapted to receive a sign card applied by a vertical sliding movement through said opening, the second frame being adapted to receive a sign card applied by a sliding movement at right angles to the direction of sliding insertional movement of the first mentioned card, whereby the latter card positively locks the former against removal from its frame.

3. A device of the character described providing a display frame, including a pair of generally similar rigid skeleton frame-forming members having a plurality of pairs of adjacent frame-forming openings therein, means interposed between and connecting the members and similar thereto in their general contour and completing the frame, said members and said means cooperatively defining channels for the reception of the edges of cards to be displayed in said frames, and a support attached to said means and extending below said members.

4. A device of the character described providing a display frame, including a pair of generally similar rigid skeleton frame-forming members having a plurality of pairs of adjacent frame-forming openings therein, means interposed between and connecting the members and similar thereto in their general contour and completing the frame, said members cooperatively defining channels for the reception of the edges of cards to be displayed in said frames and said interposed spacer means being interrupted to provide openings through which cards may be slid

into the frames, and a support attached to said means and extending below said members.

5. A device of the character described providing a display frame, including a pair of generally similar rigid skeleton frame-forming members having a plurality of pairs of adjacent frame-forming openings therein, means interposed between and connecting the members and similar to their general contour and completing the frame, said members cooperatively defining channels for the reception of the edges of cards to be displayed in said frames, said interposed spacer means being interrupted to provide entrance openings through which cards may be slid into the frames and the entrance opening for one card being through the channel of the adjacent frame, and a support attached to said means and extending below said members.

6. A device of the character described providing a display frame, including a pair of generally similar skeleton frame-forming members having a plurality of pairs of adjacent frame-forming openings therein, means interposed between and connecting the members and following their general contour and completing the frame, said members cooperatively defining channels for the reception of the edges of cards to be displayed in said frames, said interposed spacer means being interrupted to provide entrance openings through which cards may be slid into the frames, the entrance opening for one card being through the channel of the adjacent frame and the entrance opening for the other frame being disposed at right angles to the entrance opening of the first, whereby when cards are slid into position in the two frames, one card will lock the other against displacement.

7. As a new article of manufacture, a display device including a pair of rigidly connected frames, each frame having a slot at one side thereof through which flat display elements may be slidably inserted, each slot being substantially coextensive with said side, the slot for one frame being through the other at right angles to the plane of the slot of said other frame.

8. As a new article of manufacture, a display device including a pair of rigidly connected and coinciding frames, each frame having a slot at one side thereof through which flat display elements may be slidably inserted, each slot being substantially coextensive with said side, the slot for one frame being through the other at right angles to the length of the slot of said other frame and a plurality of laterally abutting character-bearing tiles applied by an endwise sliding movement through one frame and a card or the like applied by an endwise sliding movement through the other frame and when in position, blocking removal of the tiles, and means retarding withdrawal of the blocking card.

when in position, blocking removal of the tiles.

9. As a new article of manufacture, a display device including a pair of rigidly connected and coinciding frames, each frame having a slot at one side thereof and substantially coextensive with said side through which flat display elements may be slidably inserted, the slot for one frame being through the side of the other at right angles to the length of the slot of said other frame and a plurality of laterally abutting character-bearing tiles applied by an endwise sliding movement through one frame and a card or the like applied by an endwise sliding movement through the other frame and when in position, blocking removal of the tiles, and means retarding withdrawal of the blocking card.

10. As a new article of manufacture, a display device including a pair of rigidly connected and coinciding frames, each frame having a slot at one side thereof and substantially coextensive with said side through which flat display elements may be slidably inserted, the slot for one frame being through the side of the other at right angles to the length of the slot of said other frame and a plurality of laterally abutting character-bearing tiles applied by an endwise sliding movement through one frame and a card or the like applied by an endwise sliding movement through the other frame and when in position, blocking removal of the tiles, and means retarding withdrawal of the blocking card, said means comprising an abutment beyond which said blocking card is adapted to lie when fully inserted.

11. A display stand of the character described including a pair of rigid generally similar coinciding skeleton frame forming members having a plurality of pairs of aligned frame forming openings therein, means interposed between said members rigidly connected to them and spacing them apart, said interposed means similar in general contour to the frame forming members and cooperating with them to provide card receiving frames, each having an opening at one side through which a card may be slidably inserted, and a support for the stand affixed to said means and extending below said members.

12. A display stand of the character described including a pair of rigid generally similar coinciding skeleton frame forming members having a plurality of pairs of adjacent frame forming openings therein, means interposed between said members rigidly connected to them and spacing them apart, said interposed means similar in general contour to the frame forming members and cooperating with them to provide card receiving frames, each having an entrance opening at one side through which a card may be

slidably inserted, said interposed means including short lengths of stock of less width than the frame forming members whereby card receiving channels are provided in the frames, and a support for the stand affixed to said means and extending below said members.

13. A display stand of the character described including a pair of rigid generally similar coinciding skeleton frame forming members having a plurality of pairs of adjacent frame forming openings therein, means interposed between said members rigidly connected to them and spacing them apart, said interposed means similar in general contour to the frame forming members and cooperating with them to provide card receiving frames, each having an entrance opening at one side through which a card may be slidably inserted, said interposed means including short lengths of stock riveted between the frame forming members, and a support for the stand affixed to said means and extending below said members.

14. A display stand of the character described including a pair of rigid generally similar skeleton frame forming members having a plurality of pairs of adjacent frame forming openings therein, means interposed between said members rigidly connected to them and spacing them apart, said interposed means following the general contour of the frame forming members and cooperating with them to provide card receiving frames, each having an entrance opening at one side through which a card may be slidably inserted, said interposed means including short lengths of stock, some ends of which are shaped to interfit and interlock with adjacent ends of other lengths of stock and the remaining ends of which are riveted to the frame forming members.

15. A display stand of the character described comprising a pair of frame forming members having openings therein and means disposed between said members, connected thereto and spacing them apart, said means coinciding with said openings and comprising a U-shaped member, a cross bar spaced from the U-shaped member and side pieces adjacent the end of said bar and cooperating therewith and with said U-shaped member.

16. A display stand of the character described including a pair of frame forming members having openings therein and means disposed between said members, connected thereto and spacing them apart, said means comprising a U-shaped member, a cross bar spaced from the end of said U-shaped member and side pieces adjacent the end of the cross bar, some of the parts of said means engaging each other and the remaining parts being riveted to said frame members.

17. A display stand of the character described including a pair of frame forming

members having openings and means disposed between said members along the edges of said openings and connected to said members and spacing them apart, said means comprising a U-shaped member, a cross bar, a side piece between the U-shaped member and one end of said bar and additional side pieces on the other side of said bar, the ends of the bar and of said side pieces engaging each other and all the parts of said means except the side piece between the cross bar and the U-shaped member being riveted to the frame forming members.

18. As a new article of manufacture, a display device including rigidly connected upper and lower frames, the upper frame having a slot at one side thereof through which a display card may be inserted by horizontal sliding movement, said frames having a common opening affording communication between the bottom of the upper frame and the top of the lower frame and through which a plurality of laterally abutting vertically disposed character bearing tiles may be advanced through the upper frame into the lower frame by a vertical sliding movement whereby partial or complete sliding withdrawal of the upper card permits withdrawal and interchange of one or more of the character bearing tiles in the lower frame and whereby the top of the upper frame acts through the card to normally block upward movement of any of said tiles.

19. A display device of the class described, including a pair of generally similar outer frame members and spacer means interposed between and connected to them and cooperating with the outer frame members to define a pair of superimposed channeled frames, one of said frames being in open communication through an opening at one side with the other and adapted to receive a sign card applied by a vertical sliding movement through said opening, the second frame being adapted to receive a sign card applied by a sliding movement at right angles to the direction of sliding insertional movement of the first mentioned card, whereby one card positively locks the other against removal from its frame.

20. As a new article of manufacture, a display device including a pair of rigidly connected and abutting frames, each frame having a slot at one side only thereof through which flat display elements may be slidably inserted, the slot for one frame being through the other at right angles to the length of the slot of said other frame.

21. As a new article of manufacture, a display device including a pair of rigidly connected and abutting frames, each frame having a slot at one side only thereof through which flat display elements may be slidably inserted, the slot for one frame being through the other at right angles to the length of the

slot of said other frame and a plurality of laterally abutting character bearing tiles applied by an endwise sliding movement into one frame and a card or the like applied by 5 an endwise sliding movement into the other frame and when in position, blocking removal of the tiles.

22. A display device of the class described including a pair of generally similar outer 10 frame members, connecting means interposed between said members and cooperating with same, said members and said means being formed to provide three adjacent frames arranged above one another, the upper frame 15 being open along its top, the middle frame open at one side and along its bottom to afford entrance to the lower frame, to admit sign-receiving elements to said frames, and a standard upon which said display device is 20 supported, said standard being rigid with respect to said connecting means.

Signed at New York, in the county of New York and State of New York, this 3rd day of Sept., A. D. 1930.
